Primary Examiner — Joseph Kukella*Assistant Examiner* — Lavor M. Amerson(74) *Attorney, Agent, or Firm* — Meunier Carlin & Curfman LLC(57) **CLAIM**

The ornamental design for a vehicle control panel as shown and described.

DESCRIPTION

FIG. 1 is a front view of a vehicle control panel according to the new design.

FIG. 2 is a right-side view thereof.

FIG. 3 is a left-side view thereof.

FIG. 4 is a top view thereof.

FIG. 5 is a bottom view thereof.

FIG. 6 is a rear view thereof.

FIG. 7 is a front view thereof showing the vehicle control panel in an installed configuration; and,

FIG. 8 is a front right perspective view thereof showing the vehicle control panel in an installed configuration.

The portions of the vehicle control panel rendered in darker gray tones are claimed. The portions of the vehicle control panel rendered in light gray form no part of the claimed design.

1 Claim, 8 Drawing Sheets(56)
